UNITED STATES PATENT OFFICE

NICOLAS GEORGEVITCH, OF PARIS, FRANCE, ASSIGNOR TO JOSEPH ALFRED DAHME, OF PARIS, FRANCE

CENTRIFUGAL HAMMER

Application filed August 19, 1926, Serial No. 130,312, and in France August 25, 1925.

This invention relates to centrifugal hammers of the kind embodying an impact device subject to the action of centrifugal force and in which for a certain part of the revolution the centrifugal force is opposed by a cam device which then suddenly releases the impact device to strike the mandril tool-holder or other like member with which the hammer is furnished.

10 The object of the present invention is to devise improvements in the construction and arrangement of such hammers which will improve their efficiency in operation, simplify and cheapen the cost of manufacture and facilitate their manipulation in practice.

The invention consists in a centrifugal hammer of the kind referred to characterized by the feature that a rolling member is employed as the impact device.

20 The invention also consists in a centrifugal hammer of the kind referred to characterized by the feature that a freely movable ball is employed as the impact device.

The invention also consists in a centrifugal 25 hammer of the kind referred to in which the cam and rolling track upon which the impact member travels during rotation are formed integral or in one piece.

The invention further consists in a centrifugal 30 hammer according to the preceding paragraph in which the member forming the rolling track and cam presents internally a rolling surface of curvilinear form which comprises a part concentric with the axis of 35 rotation of the hammer and a part of spiral or other like form leading to the cutaway part of the cam which permits of the sudden release of the impact device.

The invention also consists in a centrifugal 40 hammer of the kind referred to in which the impact device is freely movable in a sleeve or socket adapted to be rotated by suitable means.

The invention also consists in other details 45 and arrangements hereinafter described or indicated.

The accompanying drawings illustrate two modes of carrying out the invention.

Figure 1 is a longitudinal sectional elevation of one form of hammer in accordance

with the invention, the parts being shown in position at the moment of impact.

Figure 2 is a section on the line II-II of Figure 1, the parts being shown however in the position occupied immediately before the release of the impact device by the cam. 55

Figure 3 is a longitudinal sectional elevation of one form of driving device which may be combined with the hammer, and

Figure 4 is an outside elevation of the 60 complete device showing the hammer and the driving device united together.

Figure 5 is a longitudinal sectional elevation showing a second form of centrifugal hammer in accordance with the invention, the 65 impact member being shown as just leaving the cam.

Figure 6 is a similar view to Figure 1 but showing the position of the parts at the moment of impact. 70

Figure 7 is a side elevation of the device, and

Figure 8 is a sectional plan taken upon the line V-V in Figure 3. 75

In carrying my invention into effect in one convenient manner as shown in Figures 1 to 4, I form the impact device as a rolling mass, 1, which in the construction illustrated takes the form of a ball but which may also be a roller or any member adapted to be displaced by rolling. 80

The ball, 1, is freely movable longitudinally in a driving socket or sleeve, 2, the longitudinal dimensions of which are so chosen that during rotation the sleeve or socket will not come into contact with the rolling track, 3, or the cam, 4, which is integral therewith, but in order to allow the extent of drop of the impact mass from the end of the cam to be as much as possible without at the same time unduly increasing the diameter of the hammer, the sleeve or socket is provided with a slot or opening, 5, which more or less frames or straddles the rolling track and cam during rotation. 85

According to the purpose for which the apparatus is to be employed and for any given type according to the over-all diameter of the same and the dimensions of the impact mass, the notch or slot, 5, may be of greater or less 90

depth and in some cases may be dispensed with altogether.

The driving socket or sleeve, 2, is provided with two trunnions, 6 and 7, mounted respectively in ball bearings, 8 and 9, the trunnion, 6, being solid and having keyed thereon the pinion, 10, which engages the bevel pinion, 11, secured to the shaft of the motor or other prime mover by which the hammer is rotated while the trunnion, 7, is hollow and is closed at its end by the removable plug, 12. The cavity, 13, thus formed in the trunnion acts as an oil reservoir and there is located therein a wick, 22, of which the ends are flush with the inner wall of the socket, 2, the arrangement being such that if the cavity, 13, is filled with oil (conveniently through a lateral orifice normally closed by the screw 23) the lubrication of the socket and the rolling mass is obtained during the operation of the apparatus due to the wiping by the wick of the rolling mass during the backward and forward movement of such mass in the socket.

25 The rolling track, 3, and the cam, 4, are formed integral with one another in a single piece which is provided at its lower part with an aperture or slot for the passage therethrough of the anvil, mandril, or tool-holder, 14, with which the machine is provided.

30 The internal curvature of the rolling track may vary according to the type of apparatus and the height of drop which it is desired to give to the rolling mass and may for example, comprise a circular part concentric with the axis of the guide and a part of spiral shape leading to the point of release of the impact device.

35 In the example shown in Figure 2 of the drawings the spiral part of the curve extends over an angle of 180° but the magnitude of this angle may be varied according to the purpose for which the apparatus is required and it is also possible as regards the nature 40 of the curves themselves to choose the same according to the desired height of drop of the impact device and the conditions of use provided for the hammer.

50 In operation the hammer is rotated rapidly by any suitable means and the rolling mass, 1, moves outwards under the action of centrifugal force so that it runs upon the rolling track, 3, and the cam forces the rolling mass radially inwards against the centrifugal 55 force until it reaches the end, 15, of the cam when the impact device is suddenly released to strike a blow upon the anvil or like member, 14, which transmits to the tool the blows received from the impact device. The movement of the anvil may be damped or cushioned on the one hand by a washer, 16, placed 60 between the flange, 17, and the shoulder, 18, of the casing and on the other hand by a large number of washers, 19, formed of fibre, metal, or other suitable material and clamped

65 between the flange, 17, of the anvil and the flange, 20, of the tool-carrying member, 21. The washer, 16, opposes tightening or drawing together of the shoulder, 18, which if allowed to take place would cause a binding of 70 the anvil in the casing and, moreover, the arrangement of the washers, 16 and 19, also deadens the vibrations produced by the blow of the impact member and which would otherwise be prejudicial to the safety of the apparatus.

75 In the drawings the anvil, 14, is shown independent of the tool-carrying member, 21, but in some cases these two parts may be formed in one with one another in which case the damping device may be as above described or may be replaced by any other shock-absorbing or restraining means.

80 In the form of apparatus illustrated the movement of the apparatus is controlled by an electric high speed motor, 24, upon the shaft of which is keyed the bevel pinion, 11, engaging the bevel wheel, 10, the diameters of the respective gears being chosen according to the speed of the motor so as to give the socket the desired angular velocity, it being understood that such gears may be replaced by a friction or any other suitable power transmission mechanism.

85 The motor may conveniently be arranged in the casing, 25, and as shown in Figure 4 may be directly secured upon the casing, 26, of the hammer mechanism by means, for example, of the bolts, 27. The casing, 25, may be provided with a grip for holding the apparatus and upon this grip may be disposed a switch, 28, for starting and stopping the motor.

90 In the modification of the invention shown in Figures 5 to 8, the centrifugal hammer comprises a casing, 29, of cylindrical form in the interior of which is rotatably mounted a fly-wheel, 30, carried by the shaft, 31, and adapted to be actuated by an electric motor or any other suitable form of mover.

95 In the particular construction illustrated the fly-wheel is formed of two similar parts so constructed that when they are fitted together and assembled by means of bolts there is a diametral cavity formed between said parts of cylindrical form but conveniently having one end slightly closed in order to retain within such cavity the ball or other rolling member, 32, which constitutes the impact device.

100 Upon that side of the shaft, 32, remote from the ball the cylindrical cavity carries a weight, 34, held in place by the flange, 35, engaging in a corresponding groove, the object of such counterweight being to balance the weight of the ball, 32, during the rotation of the fly-wheel.

105 The projecting parts of the fly-wheel adjacent to the ends of the cylindrical cavity are so formed as to produce grooves or chan-

nels, 35, therebetween so that the fly-wheel will not during its rotation touch the cam, 36, or the top of the punch or mandril, 37, the arrangement being such that it allows of a greater extent of drop for the impact member without increasing the over-all diameter of the fly-wheel.

At the lower part of the casing, 29, there is secured by suitable means a sleeve or casing, 38, in which is mounted the tool-carrying punch or mandril, 37, which receives the blows of the impact member, the punch or mandril being adapted to slide in the sleeve or casing and being guided in part by the walls of the latter and in part by the aperture formed in the body of the casing through which such punch or mandril passes.

A set of springs, 39, held between the closing member, 40, and the lower part of the punch or mandril serves to return the latter into its original position after the blow has been received.

It may happen that in consequence of wear upon the springs, 39, or as the result of an accident of some kind the mandril may be moved into such a position that the impact member, 32, cannot come into contact therewith in which case there is a danger of the fly-wheel breaking and in order to obviate any such unfortunate accident a certain amount of elasticity is given to the connection between the two parts of the fly-wheel by interposing shock-absorbing springs, 41, between the nuts, 42, and the connected flanges of the fly-wheel parts.

For the purpose of promoting the smooth and efficient working of the improved hammer it is found desirable to introduce some efficient means of lubrication and this may be effected by forming in the body of the hammer above the casing an oil reservoir, 43, adapted to be closed by a filling plug, 44, and having therein a wick, 45, the end of which passes through an orifice into the interior of the casing so that such end will be wiped by the ball during each revolution of the fly-wheel so that the ball will thus carry away in its revolution a certain amount of oil which will effect an automatic and continuous lubrication of the cylindrical cavity and of the punch or mandril.

The operation of the device is similar to that of the apparatus described with reference to Figures 1 to 4 and in both cases the cam is fixed in the body of the hammer and not adjustable as it has been found in practice that in hammers of small dimensions the position of the cam exercises only a secondary influence upon the direction of the blows and that in practice a fixed cam is capable of producing the same effect as a movable cam.

A rapid movement of rotation may be given to the fly-wheel by any suitable means and under the influence of centrifugal force the impact member moves outwards away

from the shaft, 31, until it comes into contact with the cam, 36, by which the impact member will be forced radially inwards against centrifugal force until it reaches the end of the cam when the impact member will be suddenly released and will strike against the punch or mandril, 9.

It will be understood that while I have illustrated a form of device in which the impact member comprises a ball it may be formed as a rolling member generally, the advantage of such rolling member being that the component tangential to the direction of impact will be considerably reduced in consequence of the rolling of the member as compared with those cases in which the blow is not accompanied by a rolling movement.

Moreover, it will be further understood that the device may be employed with more than one such rolling impact member and the arrangement of the tool-carrying punch or mandril may be varied according to the purpose for which the hammer is required.

It is to be further understood that the foregoing details of construction are given by way of illustration only and I may modify the form and construction of the various members or of the driving, guiding, or fixing arrangements which place such members into operative relationship with one another or secure them to the casings.

Having now described my invention, what I claim as new and desire to secure by Letters Patent is:

A centrifugal hammer, comprising a rotatable retaining member having a cylindrical socket, the axis of which is radially disposed with respect to the axis of rotation, a cam track surrounding said retaining member, a spherical ball freely and radially movable in said socket and directed against said track by centrifugal force, and an anvil in the path of said ball, said cam track having a portion adapted to cam said ball inwardly of said socket and also having an abrupt change of contour for releasing said ball to centrifugal force at such a point as will cause said ball, when released, to be projected freely through space against said anvil.

In testimony whereof I have signed my name to this specification.

NICOLAS GEORGEVITCH.
